UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed October 5, 1922. Serial No. 592,525.

To all whom it may concern:

Be it known that I, MANSFIELD C. CRAWLEY, a citizen of the United States of America, and a resident of Groton, in the 5 county of Tompkins and State of New York, have invented certain new and useful Improvements in Typewriting Machines, of which the following is a specification.

This invention relates to improvements in 10 typewriting machines, and more particularly to line-locking mechanism therefor, including means for sounding a line-end alarm, effecting a preliminary locking of the machine, effecting a release, and effecting a 15 final locking of the machine at the end of a line of writing.

The invention has for its objects to provide an improved mechanism for performing the functions above specified which will be 20 positive and certain in action, and to provide a simple and efficient line-locking mechanism particularly adapted for use in connection with power-operated type-writing machines such, for example, as the machine 25 shown in my prior Patent No. 1,156,061, dated October 12, 1915. The mechanism illustrated is so constructed that operation of the line-locking means prevents operation of the printing keys and also locks against 30 operation a power-operated letter-feed means, a power-operated type-bar actuating means, and a universal key-controlled release means for the type-bar actuating and letter-feeding means.

35 In the accompanying drawings, wherein the preferred embodiment of the invention is illustrated—

Fig. 1 is a vertical fore and aft sectional view of a typewriting machine provided with 40 the improved mechanism;

Fig. 2 is a detail plan view of a part of the power-operated type-bar actuating means;

Fig. 3 a front elevation, partly in vertical section showing the line-locking mechanism 45 in normal inactive position;

Fig. 4 a detail perspective view, the several parts being in normal inactive position;

Fig. 5 a detail sectional view showing the bell-ringing operation;

50 Figs. 6 and 7 detail sectional and front views, respectively, showing the preliminary line-locking operation;

Fig. 8 a bottom plan view of the right-hand margin stop and its supporting means;

Fig. 9 a section on the line 9—9 of Fig. 7 55 showing the margin stop;

Fig. 10 a detail sectional view showing the margin-release operation; and

Figs. 11 and 12 detail front and sectional views, respectively, showing the final lock- 60 ing operation.

The invention has been illustrated in connection with a power-operated typewriting machine having printing means constructed as shown in my copending application Serial No. 577,362, filed July 25, 1922, Patent No. 1,455,112 of May 15, 1923, and having letter-feeding means for the platen carriage constructed as shown in my copending application Serial No. 588,046, filed September 70 13, 1922. Only so much of such mechanisms is illustrated and described herein as is necessary to a full understanding of the present invention.

The main frame 1 of the machine is provided with a pair of transversely extending raceway rails 2 cooperating with a pair of transversely extending raceway rails 3 on the rectangular frame of a platen carriage 4 to form races for ball-bearings 5, whereby 75 the carriage with the platen 6 thereon is supported to travel transversely of the main frame. The type-bars 7, only one of which is shown herein, are pivotally supported at 8 80 in a suitable segment (not shown) in the main frame. Each type bar has pivotally held to the heel thereof the forward end of one of a segmental series of couplers or selectors 9 the rear ends of which are adapted to be raised into the path of the power-driven, 90 segmental, universal type-bar actuator 10. Each coupler 9 is formed at its rear end with a cam 11 which, when the coupler is rocked upwardly by a push-rod 12 connected with the key-lever 13 associated with said coupler, 95 is adapted to force rearwardly a segmental universal trip bar 14. The several banks of printing key-levers are fulcrumed on rods 15 in the main frame and are guided in and have their throw limited by, combined guide- 100 combs and stop-bars 16 and 17 held in the frame.

The arcuate universal trip-bar 14 is formed midway its ends with an arm 18 connected by a link 19 with the lower free 105 end of a hook or actuator latch 20 pivoted at 21 on the main frame and normally urged forwardly by a spring 22 to latching posi-

tion, as shown in Figs. 1 and 4. Latch 20 has a finger or nose-piece 23 normally engaging under an arm 24 rigid with a short actuator-pull-back crank-shaft 25 journalled in bearings 26 on the main frame, and said crank shaft is connected by a pitman 27 with the actuator 10. Trip bar 14 is held to a swinging support 28 pivoted at 29 in the main frame to permit fore-and-aft movement of the bar, while the actuator 10 is held to swinging supports 30-31 pivoted at 32-33 in the main frame to permit fore-and-aft movements of the actuator. A motor spring 34 is adapted to drive the actuator forward to impel a selected type-bar to the printing point upon rearward movement of trip bar 14 which moves latch 20 rearward and forces finger 23 out from under arm 24.

A hook 35 pivoted to arm 24 is normally urged by a spring (not shown) into engagement with a ratchet wheel 36 fixed on one end of a constantly rotating drive shaft 37. Said hook is held out of said ratchet by a cam 38 when the actuator is latched in its rear position and also during the forward or working stroke of the actuator but is permitted to engage said ratchet to temporarily couple shafts 25 and 37 for the purpose of pulling back the actuator to latched position and again storing power in spring motor 34. Shaft 37 is continuously rotated while the machine is in use, said shaft being journalled in bearings 39 in the main frame and having a pulley 40 thereon connected by a belt 41 with a pulley 42 on the shaft 43 of an electric motor 44 mounted on the main frame and constantly running during use of the machine.

A transversely extending rack 45 held to the carriage meshes with a pinion 46 fixed on the upper end of a shaft 47 journalled in a bearing 48 on the main frame. A notched feed wheel 49 fixed on the lower end of shaft 47 is alternately engaged by two feed-pawls 50-51 carried by arms 52 connected as shown with the actuator 10 so as to rock about shaft 47 during fore and aft movements of the actuator. The pawls are controlled by a cam plate 53 in such manner that pawl 50 rotates wheel 49 on the forward stroke of the actuator and pawl 51 rotates the wheel on the return or back stroke of the actuator, each pawl feeding the carriage one-half of a letter-space.

The mechanism for controlling the marginal line of the writing at the right hand side of a work sheet will now be described. The front transverse member of the rectangular carriage frame 4 is provided with a longitudinal slot 54 and a margin stop bar 55 is rigidly suspended from said carriage frame member parallel with said slot. Bar 55 is provided along its front edge with notches 56 corresponding with the graduations of the letter-feed scale plate 57 which is secured to a flange depending from the forward edge of the slotted carriage-frame member.

A right-hand margin stop 58 is slidably held to bar 55, to move longitudinally of the bar, by means of front and rear hook-lugs or channel flanges 59 and 60. A horizontally swinging latch 61, pivoted on the stop 58 at 62, has its nose normally held in one of the notches 56 in bar 55 by a spring 63. The stop 58 is adjustable along the bar by means of a finger-piece 64 extending upwardly from latch 61 through slot 54 and movable both longitudinally and transversely of said slot. The stop is released by pulling forwardly on finger-piece 64 and may then be adjusted to the desired letter-space position by lateral pressure on the finger-piece. A forwardly extending pointer or indicator arm 65 is formed on the finger-piece 64 and overlies the scale-plate 57. The main body portion of the margin stop is formed with an arm 66 extending forwardly and downwardly over the front guide rail 2 for the carriage and provided with a shoe 67 the left hand edge of which is in the same vertical fore-and-aft plane as the pointed end of the indicator arm 65.

The shoe 67 is adapted to successively engage and ride over a series of three transversely spaced inclined shoulders or cam surfaces 68, 69 and 70 on the upper edge of a transversely extending bar or vertically swinging rail 71. Shoulders 68, 69, and 70 are located at progressively higher levels in order from right to left and shoulder 70 is located substantially midway between the opposite sides of the machine frame. The several cam shoulders are spaced several letter-spaces apart transversely of the machine and control, in connection with the margin stop, in the order of their location from right to left, the sounding of a line-end alarm, a preliminary locking of the machine, and a final locking of the machine after operation of a margin-release key.

The bar 71 is pivotally held at its left hand end to the front guide rail 2 in front of said rail by means of a pivot screw 72, and the free right hand end of said bar is bent downwardly and inwardly within the main frame so as to rest loosely on the upper edge of the free forward end of a vertically swinging lever 73 pivotally held to a bracket 74 in the main frame by a pivot screw 75. A fore-and-aft swinging trip-plate 77 is pivotally held at its upper end to lever 73 by a pivot screw 78, and a spring 76, connected to bracket 74 and a lug 79 on the lower end of the trip plate in a plane at the rear of the pivot 78, serves to normally hold bar 71, lever 73, and trip-plate 77 in the respective positions thereof shown in Figs. 1, 3 and 4. In this normal condition

- the lower end of the inclined shoulder 68 is in the same horizontal plane as the lower edge of shoe 67 on the margin stop 58, and a rearwardly projecting pointed nose or cam lug 80, formed on the rear edge of the trip-plate 77, is engaged over a lug 81 formed on the forward end of a two-arm bell-clapper lever 82 and extending horizontally through a slot 83 in bracket 74 and in engagement with the upper edge of the slot. The bell-clapper lever 82 is pivotally held to bracket 74 by a pivot screw 84, said lever being formed of light spring metal and having its weighted inner end or bell-clapper 85 normally held slightly spaced from a bell 86 by reason of the engagement of lug 81 with the upper edge of slot 83. The bell 86 is held to the bracket 74 by one of the screws 92 hereinafter described.
- 10 The line-locking bail comprises fore-and-aft extending side arms 87 and 88 connected at their rear ends by a transverse locking bar 89, preferably provided with stiffening flanges projecting rearwardly from the upper and lower edges thereof. A portion of the bail bar 89 and its upper stiffening flange is cut away midway the ends of the bar to provide an opening 90 in which an upwardly and rearwardly inclined cam lug 91 or abutment 91, stamped from arm 18 on trip-bar 14, is adapted to normally freely reciprocate during movements of the trip-bar 14 by selected type-bar couplers 9. The side arms 87 and 88 of the bail are pivotally held by pivot screws 92 to the brackets 74 and 93, respectively, in the main frame to rock up and down, and the arm 87 is extended forwardly beyond its pivot 92 under the trip-plate 77.
- 15 An upstanding bail-controlling lever 94 is pivotally held by a pivot screw 95 substantially midway its ends to the bail arm 87 near the forward end of said arm. The lever 94 is formed at its upper end with a pair of vertically stepped shoulders 96 and 97, the shoulder 96 being located at the rear of and higher than shoulder 97. A spring 99, connecting the upper part of lever 94 with the forward end of bail arm 87, normally tends to rock the upper end of the lever 94 forwardly and hold a stop lug 100 on said lever against the upper edge of the bail arm, so that shoulder 96 normally lies in the path of downward movement of a laterally bent lug or abutment 98 on the forward edge of trip plate 77. Abutments 96 and 98 are normally spaced vertically a distance equal to the extent of downward movement imparted to trip plate 77 by shoe 67 on the margin stop riding up the cam shoulder 68 on bar 71. A margin-release key-lever 101 is pivoted intermediate its ends on one of the key-lever fulcrum rods 15 and is guided in, and has its throw limited by, the key-lever guide-combs 16 and
17. The release key-lever is provided with a key 102 at its forward end and is formed with an upstanding arm 103 at the rear of its pivot the upwardly and forwardly inclined free end of which loosely engages the rear edge of the lever 94 below the pivot 95 of said lever 94. A compression spring 104 yieldably holds the margin-release key lever in normal position.
- 75
- Operation.*
- The right hand margin stop is adjusted along bar 55 in accordance with the marginal space desired along the right hand side of the work sheet. As the stop approaches the center of the machine during the letter-feed movement of the carriage from right to left the shoe 67 first rides up the cam shoulder 68 thus swinging the free end of the bar or pivoted rail 71 downwardly one step from the position shown in Figs. 1 and 3, thereby depressing the free end of lever 73. This initial depression of lever 73 forces trip-plate 77 downward causing the nose 80 thereon to first force lug 81 on bell-clapper 82 downward to the bottom of slot 83, thus lifting the clapper or bell-striker 85, whereupon as lever 73 approaches the position shown in Fig. 5 (the limit of its movement by cam 68) the cam nose 80 rides off lug 81, trip-plate 77 swinging slightly forward and lug 80 thereon coming to rest on shoulder 96 of lever 94. The forward swinging of the trip-plate releases the bell-clapper lever 82, permitting the clapper 85 to drop and lug 81 to again engage the upper edge of slot 83. Owing to the resilience of lever 82 the clapper 85 may drop far enough to strike the bell 86 a sharp blow after lug 81 strikes the top of the slot, whereupon the temporarily flexed lever 82 will resume its normal position with the clapper out of contact with the bell. A distinctly audible alarm is thus sounded to warn the operator that a line of writing of the desired length is nearly completed.
- 85
- 100
- 105
- 110
- 115
- 120
- 125
- 130
- Continued travel of the carriage for a few letter-spaces causes shoe 67 to ride up over cam shoulder 69, as shown in Fig. 7, thereby depressing rail 71, lever 73, and trip-plate 77 another step to the position shown in Fig. 6. During this second downward movement of the trip-plate lug 80 thereon forces the control lever 94 on the bail downward thus lifting cros-arm 89 of the bail until the front vertical face thereof below the opening 90 engages behind the cam lug 91, as shown in Fig. 6, thereby preventing rearward movement of the universal trip-bar 14. The power-driven operating means for the type-bars is thus locked against actuation and, as the power-driven letter-feeding means is controlled by movements of the type-bar actuating means, the letter-feed mechanism for the carriage is also

locked against operation. It will also be observed that, as bar 14 cannot move rearwardly, the cams 11 on the couplers 9 will prevent upward movement of the couplers 5 in front of the actuator and also prevent any substantial movement of the printing key-levers 13. The operator will thus immediately be made aware by the sense of touch that the machine is locked against operation.

As the line-locking action just described sometimes takes place when a word of one syllable, or a syllable of a word, is only partly written, it is sometimes desirable to 15 unlock the line temporarily to permit writing a few additional letters. This is accomplished by simply depressing and releasing key 102 on the margin-release key-lever 101. The depression of this key causes arm 103 20 of key-lever 101 to rock lever 94 to the position shown in Fig. 10, thereby carrying shoulder 96 rearwardly from under lug 98 on the trip-plate, whereupon the weight of the channel bar 89 and arms 88 and 87 of 25 20 the bail at the rear of pivots 92 causes the locking bar 89 to drop down to its normal position in which aperture 90 therein is opposite stop lug 91 on the universal trip-bar 14 and shoulder 97 on lever 94 engages 30 under lug 98 on trip plate 77.

If, after actuation of key 102, the carriage is fed several additional letter-spaces sufficiently to cause shoe 67 to ride up over cam shoulder 70, as shown in Fig. 11, the 35 rail 71 and lever 73 will be further depressed, thus forcing trip-plate 77 downward another step to the position shown in Fig. 12. This additional downward movement of the trip-plate again forces lever 94 40 downward, thereby again swinging the bail to locking position and locking the machine.

In the construction illustrated the pointer 65 is so arranged with relation to shoe 67 that it indicates the point on the scale 57 at 45 which the printing point will be when the final locking of the machine takes place, but it will be obvious that the relation between the shoe and pointer may be varied so that the pointer will indicate the preliminary locking point, if desired.

By inclining stop lug 91 on the trip-bar 14 upwardly and rearwardly provision is made for the bail bar 89 to exert a cam action on the trip-bar in a direction to force 55 the trip-bar forward to normal position in the event of said bail-bar being elevated to locking position in rapid writing before the universal trip bar is fully returned by the spring 22 connected with latch 20. 60 Positive action of the line-lock is thus insured even in very rapid writing on a high-speed power-driven machine such as that illustrated and "writing through" the line-lock is prevented.

Upon return of the carriage for starting

a new line, the weight of the parts of the bail at the rear of pivots 92, and the tension of springs 99 and 76, restores the several parts of the line-locking and bell-ring- 70 ing mechanism to normal position.

What I claim is:

1. In a typewriter, the combination of type-carriers, a reciprocable type-carrier actuator, power means for reciprocating the actuator, type-carrier selecting means, keys 75 for operating said selecting means, means operable by said selecting means controlling said power means to impart a single cycle of movement to said actuator, a traveling paper carriage, means for letter-spacing the carriage at the key strokes, and line-locking means controlled by the travel of the carriage for holding said power controlling means against operation by the type-carrier selecting means.

2. In a typewriting machine, the combination with a traveling paper carriage and a universal key-operated member movable by the keys of the keyboard, of a line-locking member controlled by travel of the carriage and shiftable transversely of the path of movement of the universal member to hold said universal member against movement by the keys, and means forming coating cam surfaces on said members for forcing the universal member to normal position during initial movement of the line-locking member to locking position.

3. In a typewriting machine, the combination with a traveling paper carriage and a universal key-operated member movable by the keys of the keyboard, of a line-locking member controlled by travel of the carriage and shiftable transversely of the path of movement of the universal member to hold said universal member against movement by the keys, and a stop on the universal member provided with a cam surface along one edge movable across the path of locking movement of the line-locking member during movements of the universal member by the keys, said line-locking member being shiftable to a locking position opposite the end of said stop.

4. In a typewriting machine, the combination of key-operated type-selecting means, a single-cycle power means for actuating selected type to print, a universal trip device for releasing the power means operable by said type-selecting means, a pivotally supported locking member for said trip device normally out of the path of said device, an upstanding control lever pivotally held to said locking member and having stepped abutments at its upper end, a traveling paper carriage, a margin-controlling device on the carriage, means operable by said margin-controlling device to exert downward pressure on the higher one of said abutments at a predetermined point in the 115 120 125 130 135

travel of the carriage to actuate said locking member, a margin-release key operatively connected to rock said lever to shift the lower one of said abutments beneath said lever depressing means, and means whereby said margin-controlling device may after slight additional travel of the carriage impart additional downward movement to the lever depressing means to again actuate the locking member.

5. In a typewriting machine, the combination with a machine frame and a paper carriage traveling transversely of the frame, of a right-hand margin controlling device having a shoe thereon, a transversely extending rail pivotally held at its left end to the frame and adapted to be depressed at its other end by said shoe, line-end alarm means and line-locking means operable successively by said rail when the rail is progressively depressed, and means for yieldably supporting the free end of said rail.

6. In a typewriting machine, the combination with a machine frame and a paper carriage traveling transversely of the frame, of a right-hand margin controlling device having a shoe thereon, a transversely extending rail pivotally held at its left end to the frame and adapted to be progressively depressed at its opposite end by said shoe, a bell and a striker therefor mounted on the frame, and yieldably supported bell-striker operating means engaging under said rail and depressible thereby to actuate the striker, said striker operating means yieldably holding the rail in normal position.

7. In a typewriting machine, the combination with a machine frame and a paper carriage traveling transversely of the frame, of a right-hand margin controlling device having a shoe thereon, a transversely extending rail pivotally held at its left end to the frame and adapted to be progressively depressed at its opposite end by said shoe, a bell and a striker therefor mounted on the frame, yieldably supported bell-striker operating means engaging under said rail and depressible thereby to actuate the striker, said striker operating means yieldably holding the rail in normal position, and line-locking means operable by additional depression of the bell-striker operating means by said rail to a point below striker-actuating position.

8. In a typewriting machine, the combination with a main frame and a paper carriage traveling transversely of said frame, of a transversely extending depressible rail yieldably supported in the frame and having three transversely spaced shoulders thereon arranged from right to left at progressively higher levels, a right-hand margin controlling device mounted on the carriage in position to ride along said rail, a bell mounted in the frame having a striker, a

line-locking member pivotally supported in the frame to swing up and down, a trip device supported in the frame to move up and down and depressible successively to three different levels by the rail as the controlling device rides successively over the shoulders on the rail, means on the trip device for operating the bell-striker upon the first depression of the rail, an upstanding control lever pivoted on the line-locking member and having two stepped shoulders the higher one of which is adapted to be engaged by the trip device to depress the lever and shift the locking member to locking position upon the second depression of the rail, and a margin-release key-lever connected to swing the control lever to present the lower shoulder on said lever beneath the trip device and thus permit the locking member to return to normal position until the third depression of the rail.

9. In a typewriting machine, the combination with a machine frame and a paper carriage traveling transversely of the frame, of a right-hand margin controlling device on the carriage, a rail extending transversely of the frame and pivotally held at its left-hand end to the frame to swing up and down, a line-locking member shiftably mounted in the frame, means on the frame yieldably supporting the free end of the rail and depressible thereby to actuate the line-locking member at two different points in the travel of the carriage, said rail having stepped shoulders thereon over which the margin controlling device is adapted to ride, a control member shiftably held to the line-locking member and having stepped surfaces successively engaged by said depressible means for actuating the locking member, and a margin-release key-lever adapted to engage and shift the control member to move one of said stepped surfaces out of engagement with the depressible means and move the other stepped surface under said depressible means.

10. In a typewriting machine, the combination with a machine frame and a platen carriage mounted thereon to travel transversely of the frame, of a right-hand margin stop mounted on the carriage, a transversely extending rail pivotally held at its left hand end to the frame to swing up and down and having three stepped shoulders on the upper edge thereof arranged at progressively higher levels from right to left, a shoe carried by the stop adapted to ride along the upper edge of the rail, a line-end alarm device operable by depression of the rail as the shoe rides over the right hand shoulder on the rail, a line-locking device operable at two different points in the travel of the carriage as the shoe rides over the intermediate and left hand shoulders on the rail, and margin-releasing means for un-

locking the line-locking device after operation of said device by movement of the shoe over the intermediate shoulder.

11. In a typewriter, the combination of 5 type-carriers, a reciprocable type-carrier-actuator, power means for reciprocating the actuator, type-carrier selecting means and keys for operating the same, a transversely-extending tripping member for releasing 10 said power means to impart a single cycle of movement to said actuator, a locking member adapted to be raised to a position behind said tripping member to thereby lock the same against release action, and carriage-operated means for raising said locking member to locking position.

12. In a typewriting machine embody-

ing power-actuated type-carrier-actuating means, a swinging tripping member for said power-actuated mechanism adapted to be actuated rearwardly by one of the printing keys for tripping the type-carrier-actuator, a locking member adapted to be moved up to a position behind the tripping member to thereby lock it against rearward release 25 movement, cam means for wedging the tripping member forwardly when the locking member is thus swung to a position behind the tripping member, and carriage-operated mechanism for shifting the locking member 30 to locking position.

In testimony whereof I hereunto affix my signature.

MANSFIELD C. CRAWLEY.
